UNITED STATES PATENT OFFICE.

CARLETON W. SMITH, OF NEW YORK, N. Y., ASSIGNOR TO FOLDING-STAND COMPANY, INC., OF NEW YORK, N. Y., A CORPORATION OF NEW YORK.

DESIGN FOR A FOLDING STAND.

47,742.

Specification for Design. Patented Aug. 17, 1915.

Application filed October 13, 1914. Serial No. 866,546. Term of patent 14 years.

To all whom it may concern:

Be it known that I, CARLETON W. SMITH, a citizen of the United States, residing at New York, in the county of New York and State of New York, have invented a new, original, and ornamental Design for Folding Stands, of which the following is a specification, reference being had to the accompanying drawings, forming a part thereof, in which—

Figure 1 is a front perspective; and Fig. 2, a side perspective.

I claim:

The ornamental design for a folding stand, as shown.

CARLETON W. SMITH.

Witnesses:

HARRY A. STONE,
RACHEL PARIS.
